W. E. BOOTH

ELECTRICAL WAVE TRANSMISSION SYSTEM

Filed Nov. 22, 1919

Inventor:
Wilfred E. Booth
by C. L. Sprague, Atty.

UNITED STATES PATENT OFFICE.

WILFRED E. BOOTH, OF NEW YORK, N. Y., ASSIGNOR TO WESTERN ELECTRIC COMPANY,
INCORPORATED, OF NEW YORK, N. Y., A CORPORATION OF NEW YORK.

ELECTRICAL-WAVE-TRANSMISSION SYSTEM.

Application filed November 22, 1919. Serial No. 339,837.

To all whom it may concern:

Be it known that I, WILFRED E. BOOTH, a citizen of the United States, residing at New York, in the county of New York, State of New York, have invented certain new and useful Improvements in Electrical-Wave-Transmission Systems, of which the following is a full, clear, concise, and exact description.

- 10 The invention relates to electrical transmission systems, and has for an object to provide particularly simple and convenient forms of signaling systems, more especially radio signaling systems.
- 15 A further object is to provide a sending and a receiving system for radio communication in connection with a single antenna system, and provided with means which enables a single element in the antenna to 20 serve to receive energy from the transmitter for transmission and to apply received energy to the receiver circuit.

A further object is to provide switching systems for radio or other transmitting and 25 receiving systems so designed that upon placing the receiving system in receiving condition, the transmitting system is left in condition not to interfere therewith and vice versa.

30 A further object is to provide a signaling system with means for supplying direct current to the microphone of a transmitter apparatus from the same electrical source which is used for one or more other purposes in the system, thereby eliminating one source which heretofore has usually been provided.

A general object is to provide a commercially desirable form of wireless system for 40 two-way signaling having minimum weight, bulk and complexity of apparatus.

The essential parts of a system involving the features of this invention are diagrammatically illustrated in the accompanying drawings. All the switch contacts are shown in the transmitting position. The antenna circuit 1 comprises a suitable radiating system connected to the coil 2 through the blade or element s_6 of a gang switch 45 having six elements, namely, s_1 , s_2 , s_3 , s_4 , s_5 , and s_6 . The coil 2 is grounded through the capacity 3 thereby completing the antenna

circuit, and oscillating vacuum tube 4, has its anode connected to the coil 2 through the conductor 5, its grid connected to the coil 2 55 through the stopping condenser 6 and the switch s_4 , and the cathode connected to ground through the connection 7 of the cathode-heating circuit, shown in dotted lines, to the antenna ground. A suitable vacuum tube 8 is in parallel with the tube 4 with respect to the space current source EP and the speech frequency choke coil 10. The space current path for the direct current through the tube 4 includes the high frequency choke coil 11, conductor 12, the antenna coil 2 and the conductor 5. The input circuit 13 of the tube 8 has coupled thereto a microphone circuit 14 which includes the microphone 15 and the filament 70 16 of a vacuum tube 17 located in the receiving system. A battery or other suitable source EF provides heating current for the filamentary cathodes of the vacuum tubes of both the receiving and the transmitting systems. When receiving, however, the blade s_3 is on its point R, thereby breaking the filament-heating circuit of the transmitting tubes.

During reception the gang switch is so 80 thrown that each blade or element, s_1 , s_2 , etc. thereof contacts with its corresponding contact point R. The antenna circuit is thereby closed from the antenna 1 through s_6 , condenser 18, s_1 and conductor 19 to coil 2 85 and through capacity 3 to ground. The capacity 3, however, is short-circuited by a path consisting of conductor 12, contact s_2 , the portion 26 of the microphone circuit 14, and the dotted line heating circuit to ground. The grid of the detector 20 is connected 90 through the stopping condenser 21 and the blade s_1 to the coil 2, while the cathode of the detector 20 is connected to ground through the heating circuit. The input circuit of the tube 20 thereby comprises a suitable portion of the coil 2. All the connections to coil 2 except that of capacity 3 are variable. The waves detected by the tube 20 are repeated by the amplifiers 17 and 22 100 in a manner well-known in the art, thereby reproducing the received signals in the telephone receiver 23 or any suitable indicating instrument.

During transmission the cathode-heating circuit of the receiving tubes is energized. Since the microphone circuit 14 is shunted across a portion of the heating circuit which 5 includes the cathode 16, the microphone circuit will be energized. The microphone circuit may be shunted across any desired portion of the cathode-heating circuit, across which there is a suitable drop of potential. 10 This portion may include the filament or filaments 16 of one or more tubes and a suitable resistance 29 in the heating circuit which is external to the tubes if necessary. The variation in potential of filament 16 15 with respect to its associated anode which is induced by the reaction of the microphone circuit upon the heating circuit tends to cause side tone. Since the heating circuit of the transmitter tubes is in parallel with 20 the heating circuit of the receiver tubes, an adjusting resistance 24 is provided while a choke coil 25 serves to prevent reaction of the heating circuits upon one another. Choke 25 also serves to attenuate fluctuations from source EF. 25

The blades of the gang switch function as follows:

Blade s_1 in transmitting position connects a part 26 of the microphone circuit across 30 the input circuit of the detector 20. The small resistance which will necessarily be possessed by the conductor 26 will aid a certain amount in producing side tone in the receiver 23. In the receiving position s_1 35 connects the detector grid to the antenna coil.

In the transmitting position the blade s_2 closes the microphone circuit, while in the receiving position it serves to shunt the circuit hereinbefore referred to around the capacity 3.

In the transmitting position the blade s_3 closes the transmitter filament circuit which it opens during reception.

45 During transmission the blade s_4 connects the grid of the oscillator tube to the antenna coil, which connection is broken during reception. This prevents the grid-plate capacity of the tube 4 from acting as a shunt on

50 the coil 2. This also prevents the path including the capacity 6 and the leak path of the oscillator from shunting the capacity 3 during reception.

The blade s_5 serves during transmission 55 to close the anode-cathode circuits of the tubes 4 and 8 which it opens during reception.

The blade s_6 during transmission connects the antenna to the antenna coil 2 directly, 60 while during reception it connects the antenna to the antenna coil through the tuning condenser 18 and the blade s_7 .

By a single motion, that is, the throwing of the gang switch, the operator will be able

to change from transmitting to receiving. 65 The transmitting wave length may be varied independently of the receiving wave length, and the constants of the antenna circuit may be adjusted in the two cases to such values as may be most desirable at that instant for the particular operation being carried on. A master switch 27 may be thrown to control the entire system. Although this master switch does not open the circuit of the source 28, this is unnecessary because when the 70 cathodes of the tubes 20, 16 and 22 are not energized, the source 28 cannot deliver any current. 75

The novel features believed to be inherent in the invention are defined in the appended 80 claims.

What is claimed is:

1. In a radio system, an antenna circuit for radiation and reception, a source of high frequency signaling oscillations, a receiving 85 apparatus for translating received oscillations, an impedance element in the antenna circuit, and a switch device for operatively connecting said source and said receiving apparatus alternately to said impedance device. 90

2. In a radio system, an antenna for radiation and reception, a source of high frequency signaling oscillations, a receiving apparatus for translating received oscillations, an impedance element in the antenna circuit, 95 a switch having one position for connecting said source to said element and another position for connecting said receiving apparatus to said element, and devices for giving said antenna any predetermined one of a plurality of different natural periods in each of said positions irrespective of the natural period thereof in the other position. 100

3. A wireless transmission system comprising a thermionic oscillation generator, 105 an antenna circuit, means for connecting said antenna circuit thereto whereby said circuit primarily determines the frequency of the oscillations generated and radiates said oscillations, a receiving circuit, and common means to alternately couple said generator and said receiving circuit to said antenna. 110

4. A signaling system comprising a coil having points of connection adapted to be connected to a transmission and reception conductor, means functioning in cooperation with said coil for generating signaling waves, and means for translating received 115 signaling waves, combined with means for alternatively connecting one or the other of said means to said coil and means whereby the circuits of the disconnected generating or translating means are rendered incapable of absorbing substantial amounts of energy 120 from the connected means. 125

5. An antenna circuit, a coil included therein, a wave generating means, translat-

ing means for received waves, means for alternately connecting said generating and translating means to said coil, and means for independently establishing the tuning of 5 said circuit in each of said connected positions.

6. A radio system comprising transmitting means and a power supply therefor, an antenna coil and a gang switch, an element 10 of said switch when in a receiving position cutting off said power supply from said transmission devices, and another element thereof functioning to cut said devices from said antenna coil.

15. 7. A system in accordance with claim 6 having a microphone circuit and a third element of said switch functioning to open said microphone circuit in receiving position.

20. 8. A system according to claim 6 including a detector and another element of said switch functioning to connect said detector to said antenna coil in receiving position.

9. A signaling system comprising a transmission circuit, said transmission circuit comprising a signaling circuit including a device for producing electrical waves of signaling frequency, a receiving circuit comprising elements other than said transmission circuit and including an electron discharge device having a cathode, and a heating circuit for said cathode, said signaling circuit being shunted around a portion of said heating circuit.

35. 10. A signaling system comprising a coil having points of connection adapted to be connected to a transmission and reception conductor, a receiving circuit adapted to be coupled to said coil, a transmitting circuit adapted to be coupled to said coil, and a single control element for coupling the receiving circuit to and uncoupling the transmitting circuit from said coil.

11. A radio circuit including transmitting 45 means comprising a microphone, and a receiving circuit, comprising elements other than said transmission circuit and comprising a discharge device having a cathode, said microphone being connected across a part of said circuit including said cathode.

12. A radio system having a switch, a microphone circuit, a detector and an antenna circuit, said switch in one position connecting said detector to said antenna circuit and in another position connecting a part of said microphone circuit to said detector.

13. A radio system including a microphone circuit, a detector, an antenna circuit and a switch, said switch being adapted in one position to close said microphone circuit and in another to shunt an element of said antenna circuit.

14. A radio system comprising a radiating

conductor and a gang switch having a plurality of positions, a blade on said switch adapted in one of said positions to connect said radiating member to ground through one path and in another to connect said radiating member to ground through another path, said paths having one impedance means in common thereto, said impedance means serving as an element for coupling a transmitting circuit to said conductor in one position of said switch and for coupling a receiving circuit to said conductor in another position of said switch.

15. In a signaling system, a cathode heating circuit grounded at one point, a series of cathodes included in and adapted to be heated by a source of energy connected to said circuit, and a sound controlled variable impedance device connected across one of the cathodes of said circuit and adapted to receive energizing current by virtue of such connection.

16. In a radio transmission and reception system, an antenna circuit including an inductance, a switch for connecting said inductance alternately to a transmitter circuit 90 and a receiver circuit, a capacity included in said antenna circuit between said coil and ground during transmission, and means operated by the movement of said switch to receiving position for closing a shunt path 95 around said capacity.

17. In a radio telephone transmission and reception circuit, a receiver circuit and a transmitter circuit having their high frequency circuit elements operatively disconnected from each other at all times, a transmitting microphone, a receiving telephone, and a low frequency connection from said microphone to said telephone through said receiver circuit.

18. A signaling system comprising transmitting devices and separate receiving electron discharge devices, cathodes and cathode-heating circuits for said devices, and a voice current circuit including a device 100 for translating sound waves into electrical waves, said circuit being in shunt to a part of one of said cathode-heating circuits.

19. A signaling system comprising transmission means including a sound wave controlled device for producing electrical variations, a receiving means separate from the transmission means and including a space discharge tube having a cathode, and means including an electrical circuit for heating said cathode, said device being connected to two points of different potential in said circuit.

20. In a radio transmission and reception system, a single coil adapted to be connected in the antenna for transmission and reception, a transmitter circuit, a set of adjustable connections for connecting said transmitter

1
circuit to said coil, a receiver circuit, a set of connections adjustable independently of said first mentioned set of connections for connecting said receiver circuit to said coil, and means for changing from transmitting position to receiving position or receiving position to transmitting position without disturbing any of said sets of adjustable connections.

In witness whereof, I hereunto subscribe my name this 21st day of November, A. D. 1919.

WILFRED E. BOOTH.
